UNITED STATES PATENT OFFICE.

WILLIAM H. HART, JR., OF PHILADELPHIA, PENNSYLVANIA.

BICYCLE-SUPPORT.

SPECIFICATION forming part of Letters Patent No. 634,296, dated October 3, 1899.

Application filed December 19, 1898. Serial No. 699,679. (No model.)

To all whom it may concern:

Be it known that I, WILLIAM H. HART, Jr., a citizen of the United States, residing in the city and county of Philadelphia, State of Pennsylvania, have invented a new and useful Improvement in Bicycle-Supports, which improvement is fully set forth in the following specification and accompanying drawings.

My invention consists of a bicycle-support adapted to be journaled on the frame of a bicycle-pedal, so as to be placed in operative position thereon and when not required for service to be folded on said frame and be controlled thereon by the resiliency of the legs of the support.

Figure 1 represents a perspective view of a bicycle-support embodying my invention, the same being in operative position. Fig. 2 represents a vertical section thereof on line $x-x$, Fig. 3. Fig. 3 represents a top or plan view of the support. Figs. 4 and 5 represent perspective views of other forms of my invention.

Similar letters of reference indicate corresponding parts in the figures.

Referring to the drawings, A designates a bicycle-pedal, in whose frame B, at the forward end thereof, are the openings C.

D designates a support for the bicycle, the same consisting of the resilient legs E, the foot F, the journals L, and the elbows at the upper part of said legs, said legs being preferably made in sections which are united by the buckle G, which engages with right and left screw-threads on the inner ends of the foot F.

In the sides of the frame B are the slots N, which are adapted to receive the outer limbs M of the elbows L, said sides having corrugations H thereon, the depressions between which form the recesses J, it being seen that when the support is not in service portions of the legs E occupy the recesses J and so are held folded on the pedal-frame. When, however, the bicycle is to be supported, the legs are drawn downwardly, whereby they yield, and as they leave the recesses J they ride over the lower corrugations H. Then the legs are pressed together, so that the elbows K are

within the frame B, and the legs are turned outwardly to full extent and then let go, when 50 the limbs M spring into the slots N and so lock the legs in the operative position of the support, as shown in Fig. 1.

When the support is no longer required, the legs are pressed together, whereby the limbs 55 M are withdrawn from the slot N, and the support is then turned upwardly and portions of the legs are sprung over the sides of the frame B and seated in the recess J, thus holding the legs folded on the frame, as shown in Fig. 3. 60

In Fig. 4 the elbows P are adapted to rest against the front wall or cross-bar of the frame B, so as to retain the support in operative position; but said frame is adapted to have the legs folded thereon similar to that shown in 65 Figs. 1, 2, and 3.

In Fig. 5 the recesses Q, with which the legs are interlocked, are formed in the heads of the studs R, which are secured to the sides of the pedal-frame by nuts S or other means engaging 70 the shanks of said studs and bearing against said frame.

Having thus described my invention, what I claim as new, and desire to secure by Letters Patent, is—

1. In a bicycle-support attachable to a pedal-frame, resilient legs, a base or foot connecting the same, journals on the upper ends of said legs, and elbows on the inner ends of said journals, the end limbs of said elbows being 80 adapted to abut against said frame.

2. In a bicycle-support, a pedal-frame having a side with corrugations forming a recess, and a resilient leg journaled on said frame, and adapted to be sprung into said recess. 85

3. In a bicycle-support, a pedal-frame, openings in the end and side thereof, and a leg with a journal and elbow thereon, said journal being mounted in one of said openings and the outer limb of said elbow being adapted to 90 enter the other opening when the leg is in operative position.

WILLIAM H. HART, JR.
